DES. 2203

B. B. Hill of Chicopee, Mass.

Letters Patent No. 2203-Dated Oct. 17, 1865.

Design for the Stock of a Seal or Embossing Press.

The schedule referred to in these Letters Patent and making part of the same.

To all whom it may concern:

Be it known that I, B. B. Hill of Chicopee, County of Hampden and State of Massachusetts, have invented or produced a new and original Design for a Stock for Seal or Embossing Press; and I do hereby declare that the following is a full and exact description of the ~~same~~ ^{design} of ~~the~~ ^{the} ~~stock~~ ^{stock} being had to the photographic view.

A is a bed piece. B is the stock or arm extending upward and forward in the form of a hand. C is a socket tube embellished in an ornamental style to produce a plain, rich, ornamental design for a Seal Press to be substantially as described.

What I claim is therefore and desire to receive by letters Patent is,

The design for a Press Stock, substantially as illustrated and described.

Witnesses,

Jeremy M. Bliss, {
E. P. Burnham }

Benjamin B. Hill.
